UNITED STATES PATENT OFFICE

152,344

DESIGN FOR AN ELECTRIC FAN OR
SIMILAR ARTICLE

Carl A. Lindberg, Toledo, Ohio

Application August 4, 1947, Serial No. 140,691

Term of patent 14 years

(Cl. D26—7)

To all whom it may concern:

Be it known that I, Carl A. Lindberg, a citizen of the United States of America, residing at 4148 Carthage Road, in the county of Lucas, State of Ohio, have invented a new, original, and ornamental Design for Electric Fans or Similar Articles, of which the following is a specification, reference being had to the accompanying drawings forming part thereof.

Fig. 1 is a front elevational view of an electric fan, showing my new design;

Fig. 2 is a side elevational view of the electric fan of Fig. 1; and

Fig. 3 is a top plan view, on a somewhat larger scale, of the base section for the electric fan shown in Fig. 1.

I claim:

The ornamental design for an electric fan or similar article, as shown.

CARL A. LINDBERG.
